JOSEPH C. HARVEY, OF CHICAGO, ILLINOIS, ASSIGNOR TO JOHN T. UNDERWOOD, OF BROOKLYN, NEW YORK.

TYPE-WRITING MACHINE.

1,152,945.

Specification of Letters Patent.

Patented Sept. 7, 1915.

Application filed April 24, 1913. Serial No. 763,183.

To all whom it may concern:

Be it known that I, JOSEPH C. HARVEY, a citizen of the United States, residing in Chicago, in the county of Cook and State of Illinois, have invented certain new and useful Improvements in Type-Writing Machines, of which the following is a specification:

This invention relates to an adjustable connection between the line-space wheel and rotatable platen of a typewriting machine.

According to the present invention, the line-space wheel is connected frictionally to the platen, or in other words, the two parts are connected by means of a friction clutch, which is powerful enough to enable the line-space wheel to control the platen under ordinary conditions, but which will nevertheless yield sufficiently to permit the platen to be forced around while the line-space wheel is held stationary, whenever the necessity arises. I combine with this kind of clutch, a lock which mechanically holds the line-space wheel stationary while the operator, by means of the usual hand-wheel, applies sufficient force to the platen to rotate it to adjust any desired line of the work-sheet to the printing point on the platen. After this relative adjustment is effected, the line-space wheel may be employed in the usual manner to effect the line-feeding movements of the paper. Said lock I arrange to be released automatically by manipulation of the usual line-space lever, so that after the platen has been forcibly adjusted, the operator need pay no attention to disconnecting the lock, but at once proceeds to swing the usual lever to line-space the platen, and the lock will become automatically released.

Other objects and advantages will appear hereinafter.

In the accompanying drawings, Figure 1 is a view showing my invention as applied to the platen of the usual Underwood type of machine, of which part of the platen frame is shown. Fig. 2 is a view showing how the detent is released to unlock the line-space wheel, by means of the line-space mechanism. Fig. 3 is a view similar to Fig. 2 with the parts in a position showing how the detent is released just before the pawl enters into active engagement with the line-space wheel. Fig. 4 is a sectional view of the clutch; its means for adjusting the ten-

sion, and the method of mounting the detent locking lever. Fig. 5 is a detail perspective of the various parts of the clutch and detent locking device.

The platen 1 is fixed upon an axle 2 journaled in the ends of a frame 3, and may be rotated either by a hand wheel 4 or line-space wheel 5, the latter driven by a pawl 6 pivoted on a sliding bar 7 operated by a line-space lever 8 and returned by a spring 9. The line-space wheel 5 is frictionally clutched to the platen. This is effected by means of a disk 10, fixed upon the platen axle and disk 11, also connected to the platen axle to rotate therewith, the line-space wheel being clamped between the disks. Springs 12 clamp the line-space wheel 5 against the fixed disk 10. The disk 11 is splined to the axle 2 by a tongue 13 entering a groove 14. The disks may have their faces provided with washers 15 of fiber or other suitable friction material. The tension of the springs 12 may be conveniently adjusted by the loosening or tightening of the lock nuts 16 on the end of the platen axle 2, to compress the said springs to a greater or lesser degree.

Whenever the line-space lever 8 is operated to drive the ratchet wheel 5, the platen will also be rotated, through the described clutch. When it is desired to adjust the platen independently of the line-space wheel, the latter is held fast, in order that the clutch may slip while the platen is rotated. The locking of the line-space wheel, to prevent it from rotating while the platen is being rotatively adjusted, is preferably accomplished by locking the detent 17 in engagement with the teeth 18 of the line-space wheel. For this purpose a lever 19 is provided, having a slot 20, into which a pin 21 on the detent 17 projects, so that when the said lever 19 is moved forward, or to the right in Figs. 1, 2 and 3, the cam portion 22 at the end of the slot 20 rides over said pin 21, and prevents the detent from rising.

The feeding of the platen 1 by means of the line-space lever 8 automatically frees the detent 17 to allow the wheel 5 to turn. This is done by thrusting back the cam lever 19 to its normal inoperative position, said cam lever 19 being in the path of a projection 23 on the line-spacing bar 7, and being forced back whenever the bar is operated.

before the pawl 6 enters a tooth of the line-space wheel 5. This relieves the operator from the necessity of seeing to the freeing of the detent after the platen has been adjusted, and keeps the reciprocating line-space mechanism in constant readiness to rotate the platen without regard as to whether the clutch has been rendered inoperative or not.

For facilitating the assembling of the 10 parts, the lever 19 is mounted to swing on a collar 24 around the platen axle 2, and is prevented from becoming dislodged by a shoulder 25 on the said collar and a cupped washer 26, held in position by the hub of 15 the hand wheel 4.

Variations may be resorted to within the scope of the invention, and portions of the improvements may be used without others.

Having thus described my invention, I 20 claim:

1. The combination of a platen frame, a platen, a ratchet wheel to rotate the platen, a clutch frictionally connecting said platen and ratchet wheel, a line-space mechanism 25 to rotate the ratchet wheel, means for locking said ratchet wheel against rotation, and means for unlocking said ratchet wheel by actuating the line-space mechanism.

2. In a typewriting machine, the combination 30 with a line-space wheel and a platen, of means to afford a rotatable adjustment of the platen relatively to the line-space wheel, comprising a clutch connecting the line-space wheel to the platen, said clutch constructed to yield by the application of force 35 to turn the platen relatively to the line-space wheel, a lock adapted to be set in position to hold the line-space wheel while the platen is being forced around relatively thereto, a line-space lever, and means operated 40 by a single movement of said lever to release the lock and rotate the line-space wheel, thereby effecting a line-space rotation of the platen.

45 3. The combination with a platen and a line-space wheel, of an intervening clutch, said platen, line-space wheel and clutch forming a train permitting relative adjustment of the line-space wheel and platen by 50 the application of force, mechanically releasable means for locking one member of said train while the force is being applied to another member of said train to effect rotatable adjustment between said members, a line-space lever, and means operated thereby to release said releasable means and rotate said members.

60 4. The combination of a platen frame, a platen, a ratchet wheel to rotate the platen, a line-space mechanism to rotate the ratchet wheel, a friction clutch between said ratchet wheel and platen, means for holding said ratchet wheel from rotation while said platen is adjusted, and means controlled by 65 the line-space mechanism to automatically

release the ratchet wheel from said holding means when the line-space mechanism is operated.

5. The combination of a platen frame, a platen, a ratchet wheel to rotate the platen, 70 a line-space mechanism to rotate the ratchet wheel, a friction clutch between said ratchet wheel and platen, a detent for alining said ratchet wheel, means for locking said detent to prevent the ratchet wheel from turning 75 while the platen is adjusted, said locking means being self-holding in locking position, and means operated by the line-space mechanism to actuate said locking means to release the detent. 80

6. The combination of a platen frame, a platen, a ratchet wheel to rotate the platen, a line-space mechanism for rotating the ratchet wheel, a clutch between said ratchet wheel and platen, means for locking said 85 ratchet wheel against rotation, leaving the platen capable of rotation by force exceeding the clutch engagement, and means dependent upon the actuation of the line-space mechanism for unlocking said ratchet 90 wheel.

7. In a typewriting machine, the combination with a revoluble platen and a ratchet wheel, of means continually pressing said platen and ratchet wheel into frictional engagement for united movement, a detent co-operating with said ratchet wheel, means to coact with said detent to lock said ratchet wheel and thereby permit independent rotation of said platen, a pawl, an operating 100 lever, and means operated by said lever to unlock the ratchet wheel and actuate the pawl to drive the ratchet wheel and platen.

8. In a typewriting machine, the combination 105 with a revoluble platen, a ratchet wheel, and line-spacing mechanism, of means continually pressing said platen and ratchet wheel into frictional engagement for united movement, a detent co-operating with said ratchet wheel, means swinging through 110 a limited arc to coact, when at one end of its throw, with said detent, to lock said ratchet wheel and thereby permit independent rotation of said platen, and means co-operating with the line-spacing mechanism, 115 in the operation thereof, to throw said swinging means in the opposite direction to release said lock.

9. In a typewriting machine, the combination 120 with a revoluble platen, a ratchet wheel, and line-spacing mechanism, of means continually pressing said platen and ratchet wheel into frictional engagement for united movement, a detent co-operating with said ratchet wheel, a locking member movable 125 by hand to two positions in which to respectively lock said ratchet wheel against movement and to release it, and means controlled by the line-spacing mechanism, in the operation thereof, to mechanically move 130

said locking member from its locking position.

10. In a typewriting machine, the combination with a revoluble platen and a line-spacing wheel, of a friction clutch between the platen and line-spacing wheel, line-spacing mechanism, a locking device to lock said wheel against rotation and permit the platen to be rotated relatively thereto when sufficient power is applied to overcome the friction of said clutch, and means operated by said line-spacing mechanism to actuate said locking device to release the line-spacing wheel and then rotate said wheel to effect a line-spacing rotation of the platen.

11. In a typewriting machine, the combination with a revoluble platen and a line-spacing ratchet wheel, of a friction clutch between said wheel and platen, line-spacing mechanism comprising a line-space lever and means operated thereby to rotate said wheel, a detent spring held in engagement with the teeth of said wheel, a lock movable into position to lock the detent against the wheel and prevent the rotation of the wheel when sufficient power is applied to the platen to overcome the friction of the clutch and rotate the platen relatively to the line-space wheel, and means operated by the line-space lever during the initial portion of its movement to actuate said lock and release the detent, said lever operative by a continued movement after the detent is released, to rotate the line-space wheel and thereby effect a line-space rotation of the platen.

12. In a typewriting machine, the combination with a revoluble platen and a line-spacing ratchet wheel, of a friction clutch between said parts of sufficient power to rotate the platen when the line-spacing wheel is rotated, and permitting the platen

to be rotated by hand relative to the said wheel when the latter is held against rotation, line-spacing mechanism comprising a slide and a pawl carried thereby to engage and rotate the line-spacing wheel, a line-space lever to actuate said slide, the latter having a limited initial movement prior to the engagement of the pawl with the line-spacing wheel, a lock movable into an operative position to lock the line-spacing wheel, and means carried by said slide to move the lock to ineffective position during the said initial movement of the slide, and thereby automatically release the line-spacing wheel to permit line-space rotation thereof when the line-space lever is operated after the said wheel has been locked.

13. In a typewriting machine, the combination with a revoluble platen and a line-spacing ratchet wheel, of a friction clutch between said wheel and platen of sufficient power to drive the platen when said wheel is rotated, a spring detent to engage the teeth of said wheel to hold the latter at line-space intervals, line-spacing mechanism comprising a slide and a pawl carried thereby to drive the line-spacing wheel, said slide having a limited initial movement prior to the engagement of the pawl with the said wheel, a lever to actuate said slide, a lock movable into and out of locking position to lock said detent against the line-spacing wheel, and means carried by said slide to move said lock out of locking position during said initial movement of the slide, thereby automatically releasing the line-spacing wheel to prevent interference of the lock with the line-spacing rotation of the platen.
